YOKE AND COUPLER BUTT CONNECTION

Donald S. Barrows, Rochester, N. Y., assignor to
The Symington Company, New York, N. Y., a
corporation of Maryland

Application March 8, 1928, Serial No. 260,057

8 Claims. (Cl. 213—72)

The invention relates to draft rigging for railway cars and has special reference to the connection of the coupler stem or shank with the yoke.

The principal object of the invention, generally considered, is to provide a pivotally connected coupler stem and vertical yoke so constructed and arranged as to provide adequate bearing means permitting rolling or rocking movement during draft or buff without bringing any strain upon the pivotal connection itself.

An important object of the invention is to provide a coupler stem and yoke connection in which the pivotal connection acts simply to prevent undesired displacement of the parts, relatively large surfaces being provided for taking the thrust on draft or buff so as to relieve the pivotal connecting means of strains.

Another object of the invention is to provide a vertical yoke and coupler combination in which the thrust receiving surfaces on the former are of such character and shape as to permit rocking movement of the coupler butt at all times, as is necessary when a car travels over curved track.

Another object of the invention is to provide a vertical yoke in which the portions receiving the draft thrust are specially constructed to embody adequate reinforcement and in which the portion taking the thrust under buff acts as a reinforcement for the arms of the yoke and prevents spreading thereof.

Still another object of the invention is to provide a yoke in which the rear or bight portion is formed with a special reinforcement acting to increase the rigidity and strength.

An additional object of the invention is to provide a coupler butt and yoke combination of this type which may be used to replace one of ordinary pattern without involving any material changes in the construction of the other parts of the rigging, which will be simple and inexpensive to manufacture, easy to assemble, positive in action, efficient and durable in service, and a general improvement in the art.

To the attainment of the foregoing and other objects and advantages, the invention preferably consists in the combination and arrangement of parts to be hereinafter more fully described and claimed, and illustrated in the accompanying drawing, in which:

Figure 1 is a view partly in top plan and partly in horizontal section showing the yoke and coupler butt assembled.

Figure 2 is a side elevation thereof with a portion of the lower part of the yoke broken away 55 and in section.

Referring more particularly to the drawing, the numeral 1 designates a coupler butt or stem having its rear end formed with extensions 2 and 3 projecting above and below the top and bottom surfaces of the major portion and defining substantially vertical shoulders 4.

The yoke, indicated generally at 5, is of the vertical type and includes spaced arms 6 connected by a bight portion 7 at their rear ends and terminating at their forward ends in projections or lugs 8 which extend toward each other or inwardly, as shown. The closed or bight portion 7 is preferably reinforced by a rib or web 9 located centrally thereof, extending beyond or about the angles or corners, and having its end portions 10 merging into the arms 6 at points forwardly of the corners. The inner surface of the bight portion 7, of course, serves as a seat or abutment for the rear follower of whatever cushioning mechanism is employed in conjunction with the yoke. The gear or cushioning means is not illustrated as such is unnecessary to a proper understanding of the invention, it being sufficient that the front and rear followers 11 and 12, respectively, are indicated by dot and dash lines.

The inner surfaces of the projections 8 are curved or inclined forwardly and outwardly from their longitudinal center line, as indicated at 13, for a purpose to be explained. The forward ends of the arms are preferably reinforced by ribs or webs 14 located at the edges and projecting outwardly beyond the corners at the junctions of the projections 8 with the arms, these webs merging into the top and bottom surfaces of the arms.

Extending vertically between and formed integrally with the yoke arms 6 is an abutment or front wall member 15 which is engaged by the front follower 11, and the front surface of this member is curved or inclined rearwardly and outwardly from its longitudinal center, as shown at 16. The arms 6, forwardly of the wall 15, are preferably tapered or decreased in width toward their ends and the reinforcing ribs or normally vertical flanges 14 tapered or increased in width to a maximum adjacent the shoulders 4 to properly reinforce said arms. The space between the abutment member 15, the extensions 8 and forward portions of the yoke arms receives the enlarged rear end of the coupler butt which must, of course, be inserted from the side of the yoke by a lateral movement with respect thereto. The parts are held assembled by a vertically extending bolt 17 which passes through suitable holes 18 in the yoke arms and a hole 19 in the coupler 110

- butt, these holes, and particularly the hole 19, being sufficiently larger in diameter than the bolt to permit the coupler to move forwardly or rearwardly into engagement with the surfaces 13 or 16 without bringing any pressure against the bolt. In this way the bolt serves as a loose pivotal connection operating to hold the parts assembled while at the same time it is not subjected to any strain in service.
- 10 In the operation it will be seen that upon draft the shoulders 4 of the coupler butt engage against and are capable of rocking movement upon the surface 13, and that upon buff the rear end of the coupler butt engages against and is capable 15 of rocking movement upon the surface 16 of the abutment member, sufficient longitudinal clearance, for that purpose being provided, between the extensions 2-3 and the surfaces 4 and 13, as shown in Fig. 1. The coupler can thus accommodate itself to train movement around curves. The abutment member 15 acts as a 20 very efficient reinforcing strut preventing any spreading tendency of the yoke arms. The web 9 also serves the same purpose but to a more limited extent. The strains against the right angularly 25 projecting extensions 8 can have no ill effects owing to the provision of the reinforcing webs or ribs 14 which greatly strengthen the forward ends of the arms. It will be noted that the 30 yoke arms are preferably widened slightly where the rear end of the coupler butt is received and that the forward extremity may be reduced in width, as shown, so as to avoid excessive width in the surface engaged by the coupler butt on draft. It is believed that the construction, 35 operation and advantages will be readily apparent to one skilled in the art without further explanation.
- Having thus described my invention, I claim:
- 40 1. In combination, a coupler stem having projections at its rear end defining substantially vertical shoulders, a vertical yoke receiving the rear end of the coupler stem and having bearing surfaces located in advance of and co-acting with said shoulders and further including an integral wall portion disposed rearwardly of said stem for the full height thereof and formed with a bearing surface co-acting with the rear surface of said stem, the first named bearing surface curving 45 forwardly and outwardly from its longitudinal center and the second named bearing surface curving outwardly and rearwardly from its longitudinal center, and a pivot member extending vertically through the yoke and coupler stem, 50 with sufficient clearance to avoid undue strain on said pin upon normal relative angling between coupler and yoke, and disposed intermediate said bearing surfaces.
2. In combination, a coupler stem having projections at its rear end defining substantially vertical shoulders, a vertical yoke comprising arms receiving the rear end of the coupler stem and having bearing surfaces located in advance of and co-acting with said shoulders and further 55 including a wall connecting the arms of the yoke and formed with a bearing surface co-acting with the rear surface of the coupler stem, the first named bearing surface curving forwardly and outwardly from its longitudinal center and the second named bearing surface curving outwardly and rearwardly from its longitudinal center, and a pivot member extending vertically through the yoke and coupler stem and lying between the butt shoulders and the yoke wall, the yoke 60 and coupler stem having holes accommodating the pivot member of such size as to permit engagement of the coupler stem with the bearing surfaces without bringing strain upon the pivot member.
3. In combination, a coupler stem having projections at its rear end defining substantially vertical shoulders, a vertical yoke comprising arms receiving the rear end of the coupler stem and having inwardly extending portions providing bearing surfaces located in advance of and coacting with said shoulders and further including a wall connecting said arms and formed with a convex bearing surface coacting with the rear surface of the coupler stem, the portions of said arms lying on either side of said stem tapering forwardly and reinforced on their outer surfaces, to compensate for said tapering, from the inner ends of the inwardly extending portions to beyond said wall, and an upright member pivotally connecting the yoke loosely to the coupler stem.
4. In combination, a coupler stem having projections at its rear end defining substantially vertical shoulders, a vertical yoke comprising spaced arms receiving the rear end of the coupler stem and having transversely extending lugs providing bearing surfaces located in advance of and coacting with said shoulders and further including a wall connecting said arms and formed with a bearing surface coacting with the rear surface of the coupler stem, the first-named bearing surface curving forwardly and outwardly from its longitudinal center and the second-named bearing surface curving outwardly and rearwardly from its longitudinal center, the arms of said yoke forwardly of said wall decreasing in width toward their ends and reinforced along their edges by normally vertical flanges continued to the ends of said lugs, and an upright member loosely intersecting said stem and yoke to maintain assembly thereof.
5. A vertical yoke comprising spaced arms adapted to receive the rear end of a coupler stem and having bearing lugs adapted to coact with shoulders on said stem, and further including a wall connecting said arms and formed with a convex bearing surface adapted to coact with the rear surface of said stem, the free ends of said arms forwardly of said wall being apertured to receive an upright pin for maintaining assembly between said yoke and stem and reinforced by marginal flanges tapering from rearward of said wall to a maximum adjacent said lugs, and continued to the ends thereof to especially reinforce the junctions between said lugs and arms.
6. A vertical yoke comprising spaced arms formed to receive the rear end of an associated coupler stem and having bearing lugs adapted to coact with the forward ends of shouldered portions on said stem, and further including a wall connecting said arms and formed with a bearing surface adapted to coact with the rear surface of said stem, said arms being apertured between said lugs and wall for receiving an upright pin for maintaining assembly between said yoke and stem, the lugs on said yoke providing bearing surfaces curving forwardly and outwardly from the longitudinal center line, and the bearing surface on the wall curving outwardly and rearwardly from the longitudinal center line, the arms forwardly of said wall decreasing in width towards their ends and reinforced by normally vertical flanges continued to the ends of the bearing lugs to especially reinforce the junctions between said lugs and arms.
7. In combination, a coupler stem having up-

- ward and downward extensions at its rear portion defining substantially vertical shoulders, a yoke having vertically spaced arms terminating at their forward ends in extensions directed toward each other and co-acting with said shoulders, an abutment member formed integral with and connecting the arms of the yoke and presenting a convex surface co-acting with the rear surface of the coupler stem, and means extending through the stem and yoke for pivotally connecting said coupler stem loosely with the yoke, said arms having their forward portions formed with ribs extending outwardly beyond the corners, for reinforcing the junctions between said extensions and arms, and merging into the arms rearwardly of said abutment member. 80
8. In combination, a coupler stem having upward and downward extensions at its rear portion defining substantially vertical shoulders, a yoke having vertically spaced arms terminating at their forward ends in extensions directed toward each other and having convexly curved rear surfaces coacting with said shoulders on draft, an abutment member formed integral with and connecting the arms of the yoke and convexly curved on its front surface for co-acting with the rear surface of the coupler stem on buff, and means extending through the coupler and yoke and disposed between the yoke extensions and abutment member for pivotally connecting the coupler stem loosely with the yoke, sufficient longitudinal clearance being provided between the coupler extensions and the shoulders and abutment member to allow rolling action between said shoulders and yoke extensions on draft, and between the rear surface of the stem and said abutment member on buff. 85
